Franklin Timmons, of Washington, D.C.

Assor to

William Miller, of Providence, R.I.

Letters Patent No. 2145-Dated July 18, 1865.

Design for a Medallion of Maj. Gen. Hooker.

The schedule referred to in these Letters Patent and making part of the same.

to all whom it may concern:

Be it known that I, Franklin Timmons, of the City of Washington, D.C., have originated and produced a new model, of which the accompanying photograph is a true representation.

What I claim as my invention and desire to see deserts secure by letters Patent is The design for mezzo relief or medallion Portrait of Maj. Gen. Hooker, represented by the photograph herewith attached.

Witnesses:

Edm. J. Brown,
J. W. Peter Baumgras.
